UNITED STATES PATENT OFFICE

THOMAS BROWNLEE, OF CLIFTON, NEW JERSEY, ASSIGNOR, BY MESNE ASSIGNMENTS, TO NATIONAL NET & TWINE CO. INC., OF BOSTON, MASSACHUSETTS, A CORPORATION OF DELAWARE

TYING WEAVER'S KNOTS

Application filed December 4, 1930. Serial No. 499,882.

This invention relates to the tying of weaver's knots and in its essentials it is applicable to the tying of such knots in the forming, for example, of nets. In forming nets according to one known method certain strands are arranged in parallelism with each other, and other strands, supplied by shuttles corresponding in number to the spaces between the first strands, are each alternately knotted to the two strands separated by the space to which the particular shuttle corresponds, the first set of strands being advanced lengthwise as each knot is formed so that the meshes of the net develop diamond- or lozenge-shaped. In the forming of each knot in such an example a looped hitch is formed in each strand of the first set by causing a portion of the strand to cross first under and then over another portion thereof and to bridge the loop of the hitch, a shuttle supplying a strand of the second set is passed from the reverse side of the hitch through said loop and at one side of said loop-bridging portion of the first strand and back through the loop at the other side of said portion, thus leaving the second strand looped around said portion and its loop embraced by the hitch, and finally the hitch is constricted upon the second loop to consolidate or complete the knot. Heretofore there has been no means to control the constriction of the hitch. Consequently in being constricted, and especially if the strand was a twisted one as usual, a twisted-loop projection would form therein and become an adjunct or protuberance, or "pin-up" as it is known, on the ultimate weaver's knot, making it in that respect defective; again, there was the possibility that the tension operative to constrict said hitch as soon as it was cast off would operate, since the hitch during constriction was not controlled, to cause the hitch to slip off the end of the loop of the shuttle strand, which would produce not a weaver's knot but a slip-knot. The present invention therefore has for its object to provide for controlling the hitch of the first strand in any case of forming a weaver's knot, whether in producing a net or for whatever purpose, during its constriction about the loop of the second strand.

The drawings show the invention more or less diagrammatically,

Figs. 1, 2 and 3 illustrating in successive stages the manipulation of two strands to form a weaver's knot; Figs. 4 to 7 showing mechanism for forming such a knot in accordance with this invention and with the moving parts in progressively different positions, and

Figs. 8 and 9 are respectively a longitudinal section of the shuttle and a transverse section of the same and its race on line 9—9, Fig. 4.

Let 1 denote a table or the like having an aperture 2 for passage of the shuttle and races 3 and 4 for the shuttle above and below the table. Let it be assumed that the strand *a* with which the shuttle strand is to form the knot is held tensioned by some means, as by and between a pin 5 to which, it may be, it is tied and a drum 6 on which it is wound and which, by a spring 7 connecting the drum with the shaft 8 on which it revolves, tends to wind the strand *a* on the drum, said strand here extending up through a hole 9 in the table and a guide 10 thereon. And let 11 and 12 be any means, as two pegs, on which to form and releasably maintain a looped hitch in strand *a*. The shuttle 13 contains a bobbin 14 on which is wound the strand *b* to be knotted and which may be frictionally resisted against too free rotation as by contact with portion 14a of the shuttle, said strand being held at some point, as 15, or in the forming of a net it may be at the knot previously formed. Shuttle 13 travels back and forth in the races 3 and 4, in each direction through the loop of the hitch which is held by the pegs in bridging relation to aperture 2; it may be confined to a definite path by having a cross-sectionally T-shaped slot 13a with which the races in cross-section conform (Fig. 9).

The shuttle has projecting from that end which is its following end on its return stroke an elastic flexible tail or hitch-holder, as a piece of spring wire 16 soldered or otherwise secured thereto.

There is nothing new in the forming and releasably maintaining on means, as 11—12, of a looped hitch *a'* (Fig. 1) so that one portion *a'* of one strand crosses first under and

then over another portion thereof and bridges the hitch loop; nor in the passing, as by a shuttle 13, of another strand, as *b*, up through the loop of such a hitch at one side 5 of portion *a*² and down through the loop at the other side of said portion (Fig. 2) so as to produce, when the hitch is constricted on the thus-formed loop *b*', a weaver's knot (as in Fig. 3). The novelty in the present invention resides in means, as 16, which 10 controls the hitch until it is more or less closely constricted upon the loop of the other strand.

(That side of the hitch which portion *a*² 15 bridges I term its obverse side and its opposite side its reverse side.)

Referring, now, to Figs. 4 to 7: in Fig. 4 strand *a* is arranged as in Fig. 1 with its portion *a*² in the dotted position of Fig. 1 and 20 the shuttle has moved from the reverse to the observe side of the hitch through the loop and drawn its trailing strand *b* through said loop. The hitch is then completed by crossing portion *a*² of strand *a* over its other portion 25 thus producing space *a*^x (Fig. 1) in the loop back through which the strand *b* is next drawn by the shuttle—Fig. 5. (So far as concerns this invention the hitch might already be completed as shown by the all-solid 30 lines in Fig. 1, or so as to have loop-space *a*^x already formed, when the shuttle first moves through the loop, which in such a case it would of course do at the left of portion *a*²). In Fig. 6 the shuttle has in returning nearly 35 cleared the hitch, which is shown cast off from peg 12 and, due to the tension on strand *a*, gripping peg 11 and the upper nose of the shuttle. In Fig. 7 the shuttle has nearly completed its return flight so that the 40 hitch has slipped off its said nose and become caught on its member 16 which yields to the tension on strand *a* more and more toward peg 11 as the shuttle returns, so that the hitch closes gradually and always under the 45 control of the tail, until the tail itself finally clears the loop and springs back to its normal position (Fig. 8). Since the hitch *a*' is thus under control or held stretched, while allowed to constrict, until it is more or less 50 sufficiently reduced to throttle the loop *b*', which embraces portion *a*² of strand *a*, I avoid any possibility of forming "pin-ups", producing slip-knots or other unintended conditions.

55 It is not of course material how the shuttle is moved back and forth; what means manipulates strand *a* to form the hitch; or how the hitch is cast-off from one of the means 11—12 so long as it is held stretched, on being 60 cast off, by means of which one shall be yieldable toward the other and preferably carried by the shuttle itself.

Usually the mechanism will comprise 65 means to tension one strand (as *a*), coactive means (as 11—12) to releasably maintain

the herein described looped hitch in said strand (to wit, that form of hitch in which a portion of one strand passes first under and then over another portion thereof and bridges the loop), a shuttle movable from the reverse 70 side of the hitch through the loop thereof and at one side of the loop-bridging portion of said strand and then back through the loop at the other side of said strand-portion, whereby to loop around said portion another 75 strand (*b*) trailing from the shuttle, and means to guide the shuttle in its movement in each direction in a definite path, the shuttle having an elastic flexible hitch-holder 80 (as 16) projecting from the end thereof which follows in its backward movement and yieldable crosswise of its said path and adapted, as described, on release of the hitch from one of said coactive means, to catch and hold the 85 hitch during said backward movement of the shuttle.

But regardless of any means, as the shuttle, for effecting the manipulation of the strand *b*, my invention broadly contemplates elastic yielding means (as 16) cooperative with one 90 of said coactive means (as 11) to resist constriction of the herein-defined looped hitch upon the passing of such another strand as *b* from the reverse side of the hitch and through the loop thereof and at one side of the loop-bridging portion of the strand forming the hitch and then back through the loop and at the other side of said portion and also upon releasing the hitch from the other of said coactive means.

Indeed, in its broadest scope, given means to tension one strand (as *a*), my invention simply contemplates means (here 11—16) cooperative to maintain the herein-defined looped hitch in said strand distended while 105 being constricted and while another strand (as *b*) stands looped around the loop-bridging portion of the first strand.

Having thus fully described my invention what I claim is:

1. Mechanism for tying a weaver's knot comprising means to tension one strand, coactive means to releasably maintain the herein-defined looped hitch in said strand, and a shuttle movable from the reverse side 115 of the hitch through the loop thereof and at one side of the loop-bridging portion of said strand and then back through said loop at the other side of said strand-portion, whereby to loop around said portion another 120 strand trailing from the shuttle, and means to guide the shuttle in its movement in each direction in a definite path, said shuttle having an elastic flexible hitch-holder projecting from the end thereof which follows in 125 its said backward movement and yieldable crosswise of its said path and adapted on release of the hitch from one of said coactive means to catch and hold the hitch during such backward movement of the shuttle.

2. Mechanism for tying a weaver's knot comprising means to tension one strand, co-active means to releasably maintain the herein-defined looped hitch in said strand, and elastic yielding means cooperative with one of said coactive means to resist constriction of the hitch upon passing another strand from the reverse side of the hitch and through the loop thereof and at one side of the loop-bridging portion of the first strand and then back through the loop and at the other side of said portion and upon also releasing the hitch from the other of said co-active means.

15 3. Mechanism for tying a weaver's knot comprising means to tension one strand and means cooperative to maintain the herein-defined looped hitch in said strand distended while being constricted and while another 20 strand stands looped around the loop-bridging portion of the first strand.

4. Mechanism for tying a weaver's knot comprising means to tension one strand and means cooperative to maintain the herein-defined looped hitch in said strand distended while being constricted and while another strand stands looped around the loop-bridging portion of the first strand, one of said cooperative means being elastic and yieldable toward the other.

In testimony whereof I affix my signature.
THOMAS BROWNLEE.
